SPEED LIMITING DEVICE

Marcel Louis Mennesson, Neuilly-sur-Seine,
France, assignor to Societe Solex, Neuilly-
sur-Seine, France, a society of France

Application September 28, 1945, Serial No. 619,099
In Luxembourg December 23, 1938

Section 1, Public Law 690, August 8, 1946
Patent expires December 23, 1958

7 Claims. (Cl. 137—139)

1

The present invention relates to speed limiting devices for internal combustion engines, and especially motor-car engines, of the kind including throttle means adapted to be urged toward the closed position thereof by the suction of the engine and elastic means for elastically opposing this action of the suction.

The object of the present invention is to provide a speed limiting device of this kind which is better adapted to meet the requirements of practice than those used up to the present time and in particular which automatically ensures temporary variations of the speed limit to which the device is adjusted in response to predetermined modifications in the working conditions of the engine.

Other objects of the invention will result from the following detailed description of some specific embodiments thereof with reference to the accompanying drawings, given merely by way of example, and in which:

Fig. 1 is a diagrammatic elevational view, partly in section, of a speed limiting device made according to the present invention, the parts being shown in the respective positions that correspond to the closing of the throttle valve;

Fig. 2 is a view similar to Fig. 1, showing the parts in the positions corresponding to the opening of the throttle valve;

Fig. 3 is an elevational view of one of the control elements of this speed limiting device;

Fig. 4 is a sectional view of a detail modification of the device of Figs. 1 and 2;

Fig. 5 is a view similar to Fig. 1 showing a simplification of the embodiment illustrated by Fig. 1;

Fig. 6 is a view similar to Fig. 1 showing another embodiment of a speed limiting device according to the invention;

Figs. 7 and 8 are views, similar to Figs. 1 and 2, of a speed limiting device made according to a third embodiment of the invention;

Fig. 9 is a view, similar to Fig. 1, of a device made according to a modification of this third embodiment.

In the following description, it will be supposed that the invention is applied to the case of a carburetor for an internal combustion engine and that it is desired to provide this carburetor with a speed regulating device adapted to limit the speed of this engine, and therefore of the motor vehicle on which it is fitted, to a given maximum value.

The carburetor may be of any suitable type,

2

same as the speed regulating device proper. For instance, it includes, according to a known construction, a throttle valve 1 freely and eccentrically mounted on its axis 2 and subjected to the action of a spring 3 which tends to open the valve by applying it against an abutment 4 rigid with the member 5 through which said throttle valve is operated. Due to the eccentric mounting of said throttle valve, the suction in the induction conduit 6 of the engine through which the fuel is flowing in the upward direction (which suction varies as a function of the speed of said engine) exerts on the two portions of the throttle located respectively on either side of its axis a differential effect which tends to move the throttle toward the closed position thereof when a limit speed is exceeded, so as to bring back the engine speed to the predetermined value without the driver having to modify the position of control member 5. A second abutment 4², also provided on control member 5, limits the angular displacement of the throttle toward the closed position thereof. Spring 3 is fixed, at one of its ends, to a part 7 of adjustable position and the other end of said spring is connected to throttle 1, either directly as shown by Figs. 7 and 8, or through the intermediate of a link 8 (Fig. 1).

In the examples shown by Figs. 1 to 5, the tension of spring 3, which, as above stated, can be modified by displacing part 7, is influenced, under certain conditions, by displacements of the control member 5 of the throttle, which is operated from a distance by a pedal (not shown) and a rod 9.

The permanent adjustment of spring 3 is obtained through any suitable means, including, in the example shown by the drawing, a lever 13 (Fig. 3) adapted to be actuated by the driver and which acts, through a flexible transmission, such as a cable 14 movable in its sheath 15, upon an arm 16 adapted to move, through a pinion 17 and a rack 18, a sliding piece 19 on which part 7 is secured.

According to the present invention, displacement of said part 7, instead of being ensured only through the action of cable 14, operated by means of lever 13, can also be produced by certain displacements of the throttle valve control member. This result is obtained, for instance, by causing said member 5 to modify the position of the end of sheath 15 so that arm 16 is positively displaced in the direction that corresponds to an increase of the tension of spring 3 with-

out modifying in any way, at this time, the position of lever 13 or the like.

For this purpose, the end of sheath 15 is secured to a sleeve 20 adapted to slide axially in two bearings 21 and 22. This sleeve 20 is subjected to the action of a spring 12¹ which bears, on the one hand, on bearing 22 and, on the other hand on a flange 23 of said sleeve. The body of the carburetor includes a pivot 24 about which can rotate a finger 25 held in contact with sleeve 20 by a spring 26. The oscillation axis of finger 25 is at right angles to the sliding axis of sleeve 20 in bearings 21 and 22.

The connection between control member 5 and finger 25 may be constituted by any suitable means, for instance by a rod 27 one end of which is fixed to a part 28 freely pivoted to finger 25, while the other end of said rod is freely slidable in another part 29 pivoted to control member 5. A shoulder 30 provided on rod 27 limits the sliding displacements thereof in part 29, and this shoulder is so positioned that throttle 1 can be moved in the usual manner between its closed position (Fig. 1) and the position thereof for which the limit speed to which the device is adjusted is reached. Between these extreme positions, the speed regulating device works in normal fashion. When throttle 1 comes into a position corresponding to the above mentioned limit speed of regulation, or even a little before or a little after the throttle has reached this position, part 29 comes into contact with shoulder 30. From this time on, when the driver further depresses the throttle pedal, he pushes back finger 25 and sleeve 20, which compresses spring 12¹ in a perceptible manner. This displacement of sleeve 20 has for its effect to displace in the same direction cable 14 and arm 16, which suddenly increases the tension of spring 3 and permits a fuller opening of throttle 1 (Fig. 2). Thus the engine can develop a greater power until the increase of suction in the carburetor induction conduit, acting differentially on the throttle, corresponds to a new state of balancing with the action of spring 3.

When it is desired to return to the normal speed corresponding to the position of adjustment imparted by remote control means 13-14, it suffices slightly to release the throttle pedal until the reaction of spring 12¹ is no longer perceptible. For this position of the throttle, this spring has returned all the parts to their positions corresponding to the normal limit speed of regulation.

When it is desired to reduce the resistance opposed by spring 12¹ to the movement of the throttle pedal, the arrangement of Fig. 4 may be employed. In this case, sleeve 20 is provided with a groove 34 adapted to accommodate a ball 31 urged toward the bottom of said groove by a spring 32 housed in a radial hole 33 provided in bearing 22. In this case, the driver, when depressing the throttle pedal, perceives, when finger 25 starts being pushed back by rod 27, a resistance due to ball 31 which tends to remain in groove 34. Once the ball has been driven out of said groove, this resistance disappears, and there only remains the reaction of spring 12², which can be chosen much smaller than that of the spring 12¹ of Figs. 1 and 2.

It has been above stated that part 29 may, if so desired, come into contact with shoulder 30 a little before or a little after throttle 3 has reached a position of opening corresponding to the normal speed of regulation.

When this contact takes place a little before this position is reached, the engine can work at

high speeds with the maximum power only when the driver exerts a supplementary effort on the throttle pedal for pushing back sleeve 20 against the action of spring 12¹, thus increasing the tension of spring 3 and permitting full opening of the throttle, as above explained.

The resistance opposed to the full opening of the throttle (spring 12¹ or 12²) may be disagreeable for the driver when the latter decides to run the vehicle at maximum speed whenever this is possible.

In this case, it may be interesting to have the elastic abutment (sleeve 20 with its spring 12¹ or 12²) pushed back permanently and independently of the action of the throttle control means when the driver brings control lever 13 (Fig. 3) in the position corresponding to the highest value of the speed of regulation. For this purpose, I may, for instance, provide between arm 16 and sleeve 20, a suitable connection, either direct or indirect, for instance through link means and finger 25.

With this arrangement, when cable 14 brings arm 16 in the position corresponding to the maximum speed, this arm simultaneously pushes back finger 25 and sufficiently compresses spring 12¹ for enabling the driver fully to open throttle 1 (Fig. 2) without having to overcome the supplementary resistance of the elastic abutment constituted by sleeve 20 and spring 12¹ or 12².

On the contrary, when part 29 comes into contact with shoulder 30 after the throttle has reached the position of maximum opening to which the device is adjusted, the device above described is no longer necessary, but two distinct abutments must be provided for throttle 1 and control member 5, respectively, these two abutments being successively brought into action.

In Fig. 5, I have shown a simplified arrangement according to which finger 25¹, which is controlled by the rod 27¹ on which the control arm 5 of throttle 1 acts, does not displace sleeve 20¹ to which is fixed the sheath 15 of cable 14, but directly the element 7 of retracting spring 3. For this purpose, I dispose arm 25¹ on a fixed pivot 35 in such manner that its free end is in contact with an abutment 36 provided on a rod 37 rigid with the element 7 of spring 3. A spring 12³ wound about said rod 37, bears against a shoulder 38 thereof and a fixed point 39 of the apparatus body. This spring opposes a certain resistance to the displacement of rod 37. With this arrangement, the tension of spring 3 is increased when rod 27¹ is moved by arm 5 toward the right of the drawing and when part 29¹, carried by arm 5, comes into contact with the shoulder 30¹ of rod 27¹ which then pushes element 28 carried by arm 25¹.

This system therefore works in a manner analogous to that above described but without having any action on the control means 14-15, since the axial displacement of rod 37 by finger 25¹ does not influence the position of arm 16 in view of the fact that part 19 can slide freely in the part that carries the rack.

Fig. 6 shows another embodiment in which arm 16 (or a finger analogous to 25¹ in the embodiment of Fig. 5) is moved by means of a Bowden cable 40 (analogous to cable 14 of the above described embodiments) movable in its sheath 41 and provided with a return spring 42, or any other equivalent transmission means, controlled by at least one movable part of the gear box 43 of the vehicle when said part comes into a position corresponding to the working of a given gear combination, for instance that immediately

5

below top gear (direct drive). This movable part may be made rigid with the gear box lever 44 or be urged toward active position by the sliding gears that are brought into play for this gear combination, whereby cable 40 and arm 16 are moved toward the right when said gear combination is brought into play by means of lever 44. When lever 44 is moved away from this position, the action on cable 40 ceases and arm 16 automatically returns into its initial position under the action of return spring 42.

Owing to this arrangement, the driver, when the vehicle is in top gear, cannot exceed the speed of regulation determined by the adjustment of retracting spring 3. But when he changes to a lower gear, the third one for instance, he automatically obtains, through the operation of the gear lever 44, or through the resulting displacement of certain elements of gear box 43, an increase of the tension of said spring 3 which permits a higher speed of the engine and accordingly enables the driver to run the vehicle at a speed which may be approximately equal to the maximum speed above mentioned.

Instead of making use of the throttle pedal or the gear box for temporarily increasing the tension of retracting spring 3 and consequently the speed of regulation, I may, according to the invention, utilize any other part the displacements of which influence the working of the engine.

In Figs. 7 and 8, I have shown another embodiment of the means, operative by the throttle pedal, for permitting of temporarily exceeding the maximum speed of regulation, when so desired. In this case, I provide, for instance on throttle valve 1, an abutment 45 adapted to come into contact with the wall of the carburetor body when said throttle valve is in the fully opened position. As in the preceding embodiment, spring 3, which tends to open throttle 1, keeps said throttle applied against an abutment 41 provided on control member 5. A second abutment 42, provided on the same member, is mounted in a position such that it permits an angular displacement of throttle 1 toward the closed position thereof as long as the regulating device is working normally.

Control member 5 is provided with a finger or projection 10, adapted to cooperate with a yielding abutment constituted by a sliding rod 11 subjected to the action of a spring 12 which yieldingly opposes the thrust exerted by finger 10 on rod 11. The amplitude of movement of control member 5 and the location of finger 10 and sliding rod 11 are chosen in such manner as to obtain the following operation of the device.

When control member 5 is operated so as to displace, in the usual manner, throttle 1 from the position (shown in dotted lines in Fig. 7) for which said throttle is closed toward that (shown in solid lines in Fig. 7) for which said throttle occupies the fully opened position (abutment 45 being then in contact with the wall of the carburetor body) and the engine is running, the speed regulating device works normally.

When control member 5 is in the last mentioned position (which permits full opening of the throttle, finger 10 is brought into contact with sliding rod 11, as visible on Fig. 7. For this position of control member 5, the suction in the carburetor induction passage causes the throttle to close more or less in accordance with very principle of the regulating device.

If the driver wishes to exceed the limit speed thus determined, he exerts a stronger effort on

6

part 9, through the throttle pedal and finger 10 drives back sliding rod 11 against the action of spring 12. Control member 5 then comes into the position shown by Fig. 8 thus positively holding the throttle in the fully opened position by means of abutments 41 and 42, the action of which is substituted to that of spring 3. When the throttle pedal is fully pressed down, the throttle cannot undergo any closing displacement under the effect of the suction because it is positively held by abutments 41 and 42. If this supplementary displacement of control member 5 is not complete, throttle 1 can still close partly to a limited degree under the effect of said suction and against the action of spring 3 since, in this case, abutments 41 and 42 occupy an intermediate position between those shown by Figs. 7 and 8. When the driver permits member 5 to come back to the position shown by Fig. 7, for which spring 12 is not compressed, the regulating device can again work under normal conditions.

Fig. 9 shows a modification according to which rod 9, which is operated through the throttle pedal, acts on the control member 5 of throttle 1 not directly, as in the preceding example, but through the intermediate of amplifying means, for instance a bent lever 46 mounted on a fixed pivot 47 and linked at 48 to rod 9. The other end of lever 46 is caused to act on a roller 49 mounted on the free end of arm 5. In order to keep roller 49 in contact with bent lever 46, said roller may be engaged in a guiding slot 50 provided in said lever.

By thus transmitting the movement of the throttle pedal (rod 9) to throttle 1, during normal operation of this pedal, lever 46 acts upon control member 5 with a relatively small lever arm, which permits of operating the throttle with the desired sensitiveness, and especially when the throttle is but little opened. On the contrary, when the pedal is moved beyond the position for which the throttle is fully opened, in order to obtain its forced opening, lever 46 acts upon arm 5 with a lever arm which is considerably greater so that it suffices to move the pedal through a relatively small angle for obtaining the forced opening of throttle 1. The supplementary displacement of the throttle pedal can therefore be made very small.

In a general manner, while I have, in the above description, disclosed what I deem to be practical and efficient embodiments of the present invention, it should be well understood that I do not wish to be limited thereto as these might be changes made in the arrangement, disposition and form of the parts without departing from the principle of the present invention as comprehended within the scope of the appended claims.

What I claim is:

1. In a speed regulating device for an internal combustion engine having an induction pipe, an unbalanced throttle valve in said induction pipe mounted responsive to the suction of the engine acting in a direction tending to move said valve toward its closed position, elastic means for yieldingly opposing the action of suction on said valve, control means for actuating said throttle valve, said valve being connected with a given play with said control means, and means operatively connected with said control means for exerting a supplementary opening action on said valve in response to displacements of said control means in the valve opening direction beyond the position of said control means nearest the valve closing position which permits the maximum opening of

said valve under the effects of the opposed actions of said elastic means and said suction, and spring means resisting movement of such control means in valve opening direction during such displacements only.

2. In a speed regulating device for an internal combustion engine having an induction pipe, an unbalanced throttle valve in said induction pipe mounted responsive to the suction of the engine acting in a direction tending to move said valve toward its closed position, elastic means for yieldingly opposing the action of suction on said valve, control means for actuating said throttle valve, said valve being connected with a given play with said control means, and means operatively connected with said control means for increasing the tension of said elastic means in response to displacements of said control means beyond a given position in the valve opening direction.

3. In a speed regulating device for an internal combustion engine having an induction pipe, an unbalanced throttle valve in said induction pipe mounted responsive to the suction of the engine acting in a direction tending to move said valve toward its closed position, elastic means for yieldingly opposing the action of suction on said valve, control means for actuating said throttle valve, said valve being connected with a given play with said control means, resilient means for yieldingly opposing displacements of said control means beyond a given position in the valve opening direction, and means operatively connected with said control means for increasing the tension of said elastic means in response to displacements of said control means beyond said position.

4. In a speed regulating device for an internal combustion engine having an induction pipe, an unbalanced throttle valve in said induction pipe mounted responsive to the suction of the engine acting in a direction tending to move said valve toward its closed position, elastic means for yieldingly opposing the action of suction on said valve, control means for actuating said throttle valve, said valve being connected with a given play with said control means, manually operable means for adjusting said elastic means, and means operatively connected with said control means for operating said adjusting means to increase the tension of said elastic means in response to displacements of said control means beyond a given position in the valve opening direction.

5. In a speed regulating device for an internal combustion engine having an induction pipe, an unbalanced throttle valve in said induction pipe mounted responsive to the suction of the engine

5

acting in a direction tending to move said valve toward its closed position, elastic means for yieldingly opposing the action of suction on said valve, control means for actuating said throttle valve, said valve being connected with a given play with said control means, resilient means for yieldingly opposing displacements of said control means beyond a given position in the valve opening direction, manually operable means for adjusting said elastic means, and means operatively connected with said control means for operating said adjusting means to increase the tension of said elastic means in response to displacements of said control means beyond said position.

6. In a speed regulating device for an internal combustion engine having an induction pipe, an unbalanced throttle valve in said induction pipe mounted responsive to the suction of the engine acting in a direction tending to move said valve toward its closed position, elastic means for yieldingly opposing the action of suction on said valve, control means for actuating said throttle valve, said valve being connected with a given play with said control means, abutment means operatively connected with said control means for forcing said throttle valve open against the action of said suction in response to displacement of said control means in the valve opening direction beyond the position of said control means nearest the valve closing position which permits the maximum opening of said valve under the effects of the opposed actions of said elastic means and said suction, and spring means resisting movement of such control means in valve opening direction during such displacements only.

7. In a device as granted in claim 6, the transmission between said control means and said abutment means being adapted to insure a variable amplification increasing with the amplitude of said displacements.
